KNITTING MACHINE

Wilbur L. Houseman, Somerton, Pa., assignor to
 Standard-Trump Bros. Machine Company,
 Wilmington, Del., a corporation of Delaware

Original application January 29, 1931, Serial No.
 511,949. Divided and this application September 12, 1931, Serial No. 562,462

17 Claims. (Cl. 66—36)

This invention relates broadly to a knitted fabric and a method and machine for producing the same. More specifically it relates to a stocking embodying the fabric and a method and machine for making the stocking.

This application is a division of my application Serial Number 511,949, filed January 29, 1931 in which the fabric is claimed, the present case relating to the method and machine.

10 Heretofore it has been found desirable for various reasons to produce stockings of a type said to have a "split foot" in which the instep, being visible when low shoes are worn, is composed of suitable yarn or yarns generally similar to those used for the leg portion of the stocking, while the sole is composed of different yarn, sometimes undyed to cater to certain hygienic ideas, but in general of heavier or stronger character to better withstand wear. Such stockings generally also involve a split fabric above the heel, in which the rear of the leg above the heel is composed of wear resisting yarn where a low shoe would tend to destroy the fabric, this arrangement involving the so-called "high splice".

15 The machines heretofore used to produce such stockings involve two feeds, generally designated the sole and instep feeds in view of their particular functions, each of the feeds being associated with the usual knitting cams, etc. In such machines the upper leg is knit from a yarn at the main feed, but the lower leg, at the high splice, and the instep are knit from a similar yarn at the instep feed. Desirably, of course, the same appearance should be maintained continuously from the leg into the instep but since two yarn supplies are necessarily used, and color, weight and texture are rarely duplicated to such degree that differences escape notice, there is almost always a noticeable line of demarcation at the place

20 where change from one yarn to the other occurs. Besides this, the change is further made noticeable by any slight variations in sizes of loops occurring because of varying tensions, different adjustments of cams, etc. Obviously, this change of feeds also makes it difficult if not impossible to continue a design from the leg into the instep.

One of the primary objects of the present invention relates to the provision of a fabric or stocking having portions formed by both rotary and reciprocatory knitting in which the same yarn or yarns are continued from one portion into the other without a break; or specifically, in which a design is so continued without interruption. It is also a primary object of the invention to pro-

vide a method and machine for producing these results.

Another object relates to the provision of a fabric having designs formed therein during reciprocatory knitting, and, specifically, during both rotary and reciprocatory knitting. 5

The broad objects concerning the method and machine relate to the provision of these to produce the fabric of the type just outlined. Particularly it is the broad object to provide a method and machine whereby knitting continues at the same feed through the upper leg and the instep, specifically with the production of an uninterrupted design.

It is another object of the invention to provide 15 a method and machine in which, in the formation of a split foot stocking, knitting is begun at one feed and finished at the other feed to avoid undesirable overlapping between yarns at the two feeds. 20

Further specific objects relating to the machine are the provision of means for controlling needles for the production of designs, of means for controlling the parts to properly adjust and balance the stitches for both varying yarns and reciprocation, etc. 25

The accomplishment of these and other objects will be apparent from the following description read in conjunction with the accompanying drawings in which:

Fig. 1 is a plan view of that portion of a circular knitting machine of well known type which is particularly modified in accordance with the invention;

Fig. 2 is a side elevation of the same; 35

Fig. 3 is an elevation of a stocking embodying the features of the invention;

Fig. 4 is a plan view of the cams and other elements acting upon the butts of the needles;

Fig. 5 is a plan view of the active parts of the 40 elements showing their cooperation with needles during one of the reciprocatory periods;

Fig. 6 is a sectional plan view showing particularly the arrangements for controlling the needle cams;

Fig. 7 is an inside development of the knitting cams and associated elements;

Fig. 8 is a vertical sectional view taken approximately on the plane indicated by line 8—8 in Fig. 1;

Fig. 9 is a vertical sectional view taken approximately on the plane indicated by line 9—9 in Fig. 1;

Fig. 10 is a fragmentary sectional view showing the assembly of a trick wheel;

Fig. 11 is a plan view with parts broken away showing the needle cylinder adjusting means;

Fig. 12 is an elevation, partly in vertical section, of the same means;

5 Fig. 13 is a horizontal sectional view showing the adjusting means for the cams at the instep feed;

Fig. 14 is a side elevation, partly broken away, further showing the same;

10 Fig. 15 is a vertical section taken approximately on the plane indicated by line 15—15 in Fig. 13; and

Fig. 16 is a diagram illustrating the various events in a cycle of operation.

15 The illustrated machine is of the rotary needle-stationary cam type having independently movable latch needles. The needle cylinder 2 is carried by the ring gear 4 adapted to be rotated and oscillated through the usual clutch connections,

20 one of the intermediate driving gears being illustrated at 6 in Fig. 1. The present machine differs from the ordinary type in that, instead of being axially fixed, the ring gear 4 and needle cylinder are adapted to be moved axially. This

25 is effected by the mounting of the ring gear in an annular non-rotating member 8 mounted for sliding movement in the frame of the machine in the direction of the axis of rotation of the needle cylinder, movement thereof being effected

30 through the medium of plungers 10 passing through holes in the frame and a supporting ring 12 secured to the frame. The plungers rest upon a yoke lever 14 pivoted to ring 12 and having an extension 16 engageable by an adjusting screw 18

35 carried by a lever 20 pivoted to a bracket 22 forming part of ring 12. An adjustable screw 24 limits downward movement of lever 14. Adjustable cam following screws 26 are acted upon by cams 28 carried by the main cam disc 30, whereby

40 lever 16 may be raised and the needle cylinder lifted by the action of plungers 10.

A sinker dial 32 mounts the sinkers 34 for radial movements under the action of the usual sinker cams 36 so that they properly cooperate

45 with the needles, generally designated as 38, in the formation of stitches. As is usual, the sinker cams are mounted so as to have slight reciprocatory movements during reciprocation of the needle cylinder so that the sinkers cooperate

50 properly with the needles when moving in either direction. A slotted jack dial 40 rotates with the needle cylinder and slidably supports jacks 42 arranged to engage and actuate pressers 44 located in the needle slots and adapted to deflect

55 the hook ends of the needles. This arrangement in which pressers and jacks may be supplied to cooperate with all or certain selected needles is similar to that shown in the patent to Harold E. Houseman, No. 1,779,237, dated October 21, 60 1930. The actuating means for the jacks in the present case differ from that illustrated in this patent and will be hereafter described.

The needles, heretofore generally designated as 38, are of three types as illustrated in Fig. 5, 65 namely, long butt needles 46, intermediate butt needles 48, and short butt needles 50. There are two intermediate butt needles 48 located diametrically opposite each other and adapted to act as suture needles. On one side of the diameter

70 defined by the suture needles are the long butt needles 46 adapted to form the instep of the hosiery, and on the other side are the short butt needles 50 adapted to form the sole.

In the present machine there are two feed and 75 stitch forming points designated generally by the

numerals 52 and 53 respectively in the developed interior view of the cams, Fig. 7. These points will be designated as the instep and sole feeds, respectively. As shown in Figs. 1, 4, and 6, these feeds are angularly spaced 112.5° apart, the direction of rotation of the needle cylinder during rotary knitting being counterclockwise as viewed in plan.

5 Referring particularly to Fig. 7, the cams at the instep feed comprise the upper center cam 54, the lower center cam 56, end cams 58 and 60, stitch cams 62 and 64, and deflector cams 66 and 68. Similarly the cams at the sole feed comprise the upper center cam 70, the lower center cam 72, end cams 74 and 76, stitch cams 78 and 80, and a 15 guard cam 81. Raising pickers 82 and 84 of the usual type are associated with the sole feed only. A lowering picker 88 of the usual form is provided, being located diametrically opposite the sole feed. A switch cam 86 mounted on a pivoted 20 shaft and urged by a spring 87 to the position illustrated in Fig. 7, is designed to engage only the long butt needles to elevate them when they move in one direction and yield upwardly against the action of spring 87 when they move in the 25 opposite direction to allow them to pass. A main switch cam 90, the operation of which will be later pointed out, is also provided, being positioned as illustrated in Figs. 4 and 7.

30 Cams 62 and 66 are carried by a radially reciprocable slide 92 and cams 64 and 68 are carried by a similar slide 94. These slides are provided respectively with adjustable screws 96 and 98 adapted to be engaged under the tensions of springs 101 and 103 with upwardly projecting 35 ears 100 and 102 formed on a yoke 104, (Fig. 8), pivoted to the frame and oscillatable, under the action of a plunger 106 when lifted by cams 108 on the main cam disc 30, to simultaneously retract the two slides. The two slides may be separately washered up to balance the stitches formed 40 during reciprocation.

The slides 92 and 94 are mounted in a segmental cam carrying member 110 which also forms the support for the fixed cams 54, 56, 58 and 60 at the instep feed. As shown in Figs. 13, 45 14 and 15, member 110 has journaled therein elements 112 threaded at their lower ends and fixedly carrying pinions 114 which, acting together with the heads of the elements, prevents 50 relative axial movements between the elements and member. The pinions 114 mesh with teeth on an arcuate rack bar 116 which is constrained to arcuate movement about the center line of the needle cylinder by pins 118 extending through 55 slots therein and carried by brackets 134 fixed to the non-rotating member 8, which, as brought out previously moves vertically with the needle cylinder. A forked end 120 of rack bar 116 embraces the upper end of an upstanding arm of a 60 lever 122 pivoted to the frame at 124. A spring 126 urges the lever to a limiting position defined by an adjustable screw 128, the lever being rocked at proper times against the action of the spring by engagement of a follower screw 130 carried thereby with cams 132 on the main cam disc. The elements 112 are threaded into tapped holes in brackets 134 and accordingly rocking movements 65 imparted to lever 122 will cause simultaneous upward and downward movements of the cams at the instep feed relative to the cams at the sole feed, initial adjustment being readily effected by screw 128, and the amount of movement by a cam 132 being adjusted by screw 130. The arrangement is such that action of a cam 132 produces 70

75

downward movement of the knitting cams. It may be pointed out that 110 is carried by member 8 so that, in the absence of action by cam 132, the cams associated with 110 move with the 5 needle cylinder in its axial movements.

The main switch cam 90 is carried by a shaft 136 to which is affixed a pin 138 projecting into an oblique slot 140 in the fixed supporting sleeve. An arm 142 carried by the shaft 136 is urged 10 downwardly by a spring 143 and is arranged to be engaged by a cam element 144 carried by a rocker 146 pivoted at 148 to the frame and having a downward extension 150 carrying a cam follower 152 engageable by cams 154 on the main cam disc, (Fig. 9). A spring 156 normally urges 15 the follower in a direction to contact with the cams. The pin and slot connection causes the switch cam to ride away from the cylinder when lowered so that only long butt needles are engaged. On the other hand, when it is in raised 20 position, it engages all of the butts regardless of length to lower the needles.

A second cam element 158 is adapted to rock the lever 160 which is operative when so acted upon 25 to lower the picker 88 to an inoperative position between the levels occupied by the butts of active and inactive needles as they reach its location.

Cam 78 is carried by a radially movable slide 30 162 carrying an adjustable follower screw 164 urged by a spring 166 into contact with a lever 168 arranged to be rocked to move the slide outwardly by a plunger 170 acted upon by a cam 171 on the main cam disc. Similarly cam 80 is carried by a slide 172 carrying an adjustable follower screw 174 urged by a spring 176 into contact 35 with a lever 178 arranged to be rocked to move the slide outwardly by a plunger 180 acted upon by a cam 181 on the main cam disc. It is accordingly to be noted that the cams 78 and 80 are independently movable as contrasted with the corresponding cams at the instep feed. The cam cylinder at the sole feed is centrally split as shown in Figs. 4 and 7 so that the sections may be separately washered up to balance the stitches.

At the instep feed are several yarn feeding fingers 182, in the present instance five, one of which may carry the main or body yarn, another the yarn used to form the extended top, and the others the yarns for striping and plating. In the case of plating, one or more fingers may carry a plurality of yarns. Similarly, at the other feed there may be a plurality of fingers 184; for example, one of them may carry the yarn forming the high splice above the heel, another the heel and toe yarn, and a third one the sole yarn. Any of these fingers 184 may carry a plurality of yarns for the production of plating; a plated high splice being particularly frequently desirable. A fancy 50 high splice may be formed by feeding both body and plating yarns through the first of the fingers. The means for changing yarns at the feeds is preferably of the type illustrated in the patent to Harold E. Houseman, No. 1,161,677, dated November 23, 1915. The means for producing striping at the instep feed may be similar to that shown in the patent to Harold E. Houseman, No. 1,769,580, dated July 1, 1930.

As is usual, one of the driving gears 6 is formed 0 with a cam groove 188 adapted to produce oscillation of a lever 190 which carries a pivoted pawl which engages a ratchet wheel 192 carried by a pattern chain drum 194 to produce intermittent movements of the latter. The drum in this case 5 carries two chains 196 provided with lugs 198 at

properly spaced intervals. The lugs on one chain are adapted to engage a lever 200 pivoted to the frame on a pin 202 and urged against a stop 204 by a spring 206. This lever has a lateral extension 207 on which is pivoted a pawl 208 engageable with teeth 210 of a ratchet wheel secured to a trick wheel 212. As shown in Fig. 10, the trick wheel 212 is axially slotted to receive tricks 214 having butts broken out in the usual fashion to determine the production of patterns. 10 These tricks are maintained in position by an interengaging arrangement at their lower ends and a spring band 216.

A second lever 218, also pivoted on pin 202 is arranged for engagement by the lugs on the inner chain, its movement being limited by an adjustable stop 220. An adjustable screw 222 is carried by a lever 224, pivoted to the frame at 15 225, so as to be engaged and lifted by the lever 218 when it is raised by a lug on the chain. The 20 lever 224 carries a roller 226 which, during oscillation of the lever, engages a cam member 228 carried by a lever 229 to thereby impart reciprocating movements to a link 230 pivoted at one 25 end to the lever 229 and at its other end to a lever 232 carrying a pawl 234 engaging a ratchet wheel secured to a trick wheel 238 corresponding to trick wheel 212. A spring 236 serves to return the various connected elements.

The two trick wheels cooperate with identically corresponding elements so that only those associated with the trick wheel 212 will be described. A number of levers 240, one corresponding to each height of butts of the tricks, are pivoted about a common upright pin and are adapted to be rocked by engagements of their outer ends by the trick butts. These levers engage corresponding cam levers 242 having elongated slots through which passes an upright pin 243, the levers being drawn by springs 246, one for each, 30 against adjustable stops 244. The ends of levers 242 engage the stacked cams 248 pivotally mounted on a common pin 249, these cams in turn acting upon the jacks 42. Each of the cams 248 has a lug engageable with an edge portion 35 247 of a corresponding lever 242 and capable of dropping into a depression 251 therein when the lever is rocked by the action of a butt. The edge portions 247 are parallel or concentric with the portions of the opposite edges of the levers which engage the adjustable stops so that movements of the levers 242 do not affect cams 248 until the lugs thereof can drop into the depressions. The springs 246 not only serve to pull the levers rearwardly but also serve to swing them about pin 40 45 243 until they engage a pin 250 of semicircular cross-section, this position being assumed when there is no butt engaging a lever 240. Under these conditions the cams are forced inwardly to cause deflection of the needles. If, however, 60 a butt engages a lever 240, the lever 242 corresponding thereto will be moved to a position such that the lug of the corresponding cam may drop into depression 251. The cam will then not be backed up so as to cause deflection of the needle. 65 The operation is somewhat similar to that occurring in the machine illustrated in the patent to Harold E. Houseman No. 1,779,237, dated October 21, 1930.

The semicircular pin 250 is arranged to be 70 rocked about its axis by an extension 252 of a lever 254 pivoted to the frame and provided with an adjustable follower screw 255 engageable by cams 258 on the main disc. When the pin 250 is rocked by a cam 258, it moves all of levers

- 242 the same as they would be moved by butts on the tricks. Accordingly, the fingers 248 are rendered inoperative to deflect the needles irrespective of the movements of the trick wheel. The 5 necessity of this action will be hereafter pointed out. Corresponding to lever 254 is a lever 260 which, when acted upon by either of two cams 262, serves to produce a corresponding action on the opposite side of the machine.
- 10 The outer chain 198 carries a pin 266 arranged to cooperate with a member 268 carried by lever 270 which has a cam following end 272 adapted to cooperate with a suitable cam on the disc 30. A pawl 274, pivoted to the lever 270, and having its 15 motion under the action of a spring 278 limited by an adjustable screw 276, is adapted to impart movement to the ratchet wheel 192. The lever 270 carries a guard (not shown) which acts to raise the pawl carried by the lever 190 so that it will be inoperative at predetermined times to advance the pattern chains. This mechanism is of the type fully described in the patent of Harold E. Houseman, No. 1,805,697, dated May 19, 1931, and is operative to insure the proper beginning 20 of the pattern producing cycle of operation at the initiation of the knitting of each stocking.
- 25 The various elements of the machine and their relative relationships having been described, there will now be taken up the operation of the 30 machine in the production of a stocking.
- 30 A stocking typical of those which the machine is adapted to produce is illustrated in Fig. 3. This stocking comprises a ribbed top *a*, produced as usual on a rib machine and transferred 35 to the needles of the plain fabric machine, an extended top *b*, which may be omitted, consisting of several circularly knit courses, the leg *c* circularly knitted and in the present instance composed of fancy fabric which extends continuously into the instep and the upper part of the 40 foot as indicated at *e* and *h*, the high splice *d*, the heel *f*, the split sole *g*, the advanced toe *i*, which may be omitted, if desired, consisting of several circularly knit courses, the toe *k*, and 45 loopers rounds *l*. The composition of these parts 50 of the stocking and their production will be clear after the description of the operation. The parts knitted at the sole feed, particularly the high splice, may be formed of a plurality of yarns in plated relationship.
- 55 In Fig. 16 there are graphically illustrated the events occurring in the formation of a complete stocking, the operative or inoperative conditions of various elements being plotted against the sixteen periods (some of which are idle) defined 60 by the sixteen steps of the main cam disc 30. The various periods are designated by the operations effected therein. The periods of rotation and reciprocation are designated at the bottom of the figure.
- 65 When the machine is in the stationary condition the needles are levelled to receive the rib top. At this time as indicated in the figure, fingers 182 and 184 are raised out of action, cams 62, 64, 66 and 68 and cams 78 and 80 are fully 70 retracted to disengage all of the needle butts, switch cam 90 is raised and in inner position and there is no cam 154 acting on follower 152 and accordingly the switch cam occupies the position just noted and the lowering picker 88 occupies its inoperative position intermediate the levels assumed by the butts of raised and lowered needles during operation. The pickers 82 and 84 ride the butts. The pattern chain is stationary, and controls 254 and 260 are active to prevent any deflection of the needles.

75 Following the transfer of a rib top *a* to the needles, the machine is started to knit a few rounds of yarn similar to that in the rib top to form the portion *b* known as the extended top. Upon starting of the machine the cam disc 30 is advanced one step. Cams 62, 64, 66 and 68 are allowed to move inwardly in the usual fashion, first dropping against the short butts and then subsequently moving on into the cylinder as the long butt needles pass through. The yarn finger 10 182 which carries the extended top yarn drops in advance of the first needle to knit which will be the advancing medium butt suture needle 48. The switch cam 90 is still raised so as not to affect the operation. The cam 86 swings up during 15 each revolution to allow long butt needles to pass, motion of the needles during revolution being from right to left as viewed in Fig. 7.

20 At each of the feed points the sinkers are retracted and then advanced in a wave in the conventional manner even though the needle cams may not be in operation. Accordingly, because of fabric tension, fabric loops will sometimes tend to climb up the needles at the sole feed, where at this time no knitting is taking place, in the 25 space where the sinkers are retracted. If this were permitted, when the sinkers moved in these loops would be above the nebs of the sinkers and out of control and would not be moved below the latches at the instep feed, thereby failing to cast 30 off.

25 In order to avoid this climbing of the loops at the idle sole feed, the stitch cam 80 is permitted to move in against the needle cylinder. This puts an upward wave in the needles before the 35 sinkers are retracted. Accordingly, the loops occupy a lower position on the needles and when the needles are again lowered by the top center cam 70 the fabric loops are drawn down against the stitch drawing edges of the sinkers, and the 40 nebs are well above the loops as they move in.

50 Except for the parts mentioned, the positions held before starting are maintained.

55 During this period, accordingly, several courses of plain fabric are knitted on all of the needles 45 at the instep feed 52.

After the extended top is completed the cam disc is advanced another step and rotary knitting of the upper leg starts. As the movement of the cam disc takes place, the extended top yarn finger is withdrawn and another finger, or plurality of fingers, carrying yarns suitable for the leg, are dropped into action. Of course, if striping is to take place, the fingers originally dropped into action may be replaced by others during the formation of the leg in the usual manner, for example, by the mechanism illustrated in the patent to Harold E. Houseman, No. 1,769,580.

60 During this period the fingers 184 remain inactive, and the stitch cams at both feeds and 60 switch cam 90 retain their previous positions. Accordingly, stitches are formed solely at the instep feed.

65 In the present machine, in order to illustrate the mode of production of fancy fabric, there is 70 illustrated specifically an arrangement for producing designs by reverse plating. However, from this it will be obvious that numerous other types of fancy effects may be produced, utilizing the same general principles, for maintaining a design 70 from the leg through the instep.

75 As pointed out above, two trick wheels, stepped around by means of pattern chains control the production of reverse plating by deflection of needles during the loop drawing periods. Refer- 75

ring to Figs. 1 and 7, it will be clear that during rotary knitting, when the needle cylinder rotates in a counterclockwise direction, only the trick-wheel 212, which serves to determine the deflection of needles when acted upon by cam 62, need be operative. Accordingly, during rotary knitting of the leg the control 254 must become inoperative to prevent deflection of the needles but control 260 remains operative to prevent deflection 10 of the needles at cam 64, the deflection of needles when not needed being objectionable.

While on the subject of the pattern mechanism, it will be well to point out the preferred set up of the trick wheels. Since the trick wheel 212 is used for all of the courses during rotary knitting, there must be a complete trick pattern 15 set up thereon. However, in the case of the trick wheel 238, which is effective only during reciprocation, the pattern need only be set up on tricks 20 in every other slot corresponding to the courses for which it is active, assuming, of course, that the trick wheels are stepped about at every revolution or reciprocation. Of course the stepping 25 may be such that it would be necessary to supply the trick wheel 238 with a full set of tricks. In any case it would do no harm to so supply this trick wheel. It is to be noted that during rotation or a counterclockwise reciprocation deflection 30 of a needle at the time it rides over cam 64 would produce no effect, the same being true with respect to needles acted upon by cam 62 during a clockwise reciprocation.

A reverse plated split foot fabric could be made with only a single trick wheel associated with the 35 rotary stitch cam 62 by setting up a pattern with tricks in alternate courses. Reverse plating would then take place only on alternate courses during rotary knitting and would continue on alternate courses during reciprocatory knitting. This produces a pattern effect similar in appearance, though not in construction, to that described in my Patent No. 1,805,624. There will be more 40 fully discussed below a further possible mode of operation involving not only the utilization of a single trick wheel but also other modification of a 45 the mechanism.

Proceeding with the rotary knitting of the leg, the pattern chains, starting from an initial position determined by pin 266, etc., will accordingly 50 control trick wheel 212 with the resultant production of a reverse plated pattern, deflection of needles at cam 64 being preferably avoided by the continued activity of control 260.

In a split foot stocking it is customary to begin split work well above the heel so that a stronger wear resisting fabric may be made at the back above the heel. Split work commences with another step of the main cam disc, the rotation being changed to reciprocation, the range of 55 which is, in the present machine, 360°. Inasmuch as the pattern is to be continued as indicated at e, the same fingers 182 remain active. The finger 184 which carries the high splice yarn or yarns is lowered into action. Cams 62, 64, 66 and 68 are now withdrawn part way so as to clear 60 the short butt needles but still engage the long and medium butt needles. Cam 78 moves into action, joining cam 80 which is already in active position. An intermediate length step of a cam 70 154 engages follower 152 so that switch cam 90 is lowered and simultaneously moved outwardly so that it will engage and raise long butt needles but miss short and intermediate butt needles. The lowering picker 88, however, retains its inactive 75 position since the cam 158 is so designed as not

to release lever 160 when the lever 148 is rocked only part way by the intermediate step of a cam 154. The pattern chain continues to move without interruption. The control 260 becomes inoperative so that needles may be deflected as determined by trick wheel 238. Because of reciprocatory knitting the usual take up sweeps through which the yarns at both feeds pass are rendered active. 5

The extreme position of the needle cylinder locates the needles in positions approximately 180° removed from those illustrated in Fig. 5. That is, the suture needles 48 are adjacent the two switch cams, the long butt needles are located adjacent the sole feed 53, and the short butt 15 needles adjacent the instep feed 52.

Assuming first a counterclockwise reciprocation of the needle cylinder the intermediate butt needle which leads the long butt needles rides up cam 64 and is depressed by center cam 54 and 20 stitch cam 62 taking a yarn or yarns at the instep feed. It then rides up cam 58, passes switch cam 90, by which it is not engaged, and follows the short butt needles up over cam 80 and below cams 70 and 78 taking the high splice yarn at 25 the sole feed and thereby forming a suture between the yarns at the two feeds. The long butt needles follow this suture needle through the cams at the instep feed and also take yarn there. However, the long butts do engage the switch 30 cam 90 and are raised thereby so that they ride above the cams at the sole feed 53.

The intermediate butt needle 48 which follows the long butt needles and precedes the short butt needles starts from a position adjacent switch 35 cam 90 and rides up the end of cam 80 until it engages the picker 84 by which it is raised whereupon it follows the long butt needles through the cams at 52 taking the main yarn or yarns there and finally reaching a position adjacent switch 40 cam 90 without being raised thereby. The short butt needles following this intermediate butt needle ride over cam 80, beneath the picker 84, are moved downwardly by cams 70 and 78 to take the high splice yarn, pass switch cam 86 without 45 engagement and likewise pass the partially retracted cams 64 and 62 without engagement. This partial retraction avoids the necessity of raising the short butt needles thereabove.

In a clockwise reciprocation a reverse series of 50 events occur, the positions of the parts being illustrated in Fig. 5 for approximately 180° of such reciprocation. In this case the switch cam 86 takes the place of switch cam 90 and likewise picker 82 lifts the medium butt needle leading the 55 short butt needles.

From the above it will be seen that the yarn or yarns at the instep feed are knitted by the long butt needles and both of the medium butt needles on each reciprocation. The high splice 60 yarn at the sole feed is knitted by the short butt needles and that medium butt needle which leads the long butt needles in that stroke. It is to be observed that this alternate suture operation of the medium butt needles forms a substantial 65 but non-bulky seam by the avoidance of excessive yarns in the loops thereof.

During the above, the alternate selection action of the two trick wheels proceeds to produce the pattern. Since the patterning occurs at the 70 instep feed there is no break at the change from rotation to reciprocation. While short butt needles may, and generally would, be deflected at the instep feed, there would be no result effected thereby since they take no yarn at that point. 75

Alternate trick wheel action produces the reverse plating. However, the left trick wheel will be pressing back needles while the cylinder travels clockwise but no reverse plating is effected thereby since the needles are not then forming stitches at this point. This occurrence is illustrated in Fig. 5 in which needles are shown deflected at both sets of cams 248.

When the knitting of the heel is to begin, the main cam disc is again given an intermediate movement, and the parts operate to produce the heel in substantially the conventional manner. At this time, in order to prevent interruption of the pattern, the pattern chain is stopped in the usual manner by the action of a suitable cam upon the lever 272. Both controls 254 and 260 are rendered operative to prevent unnecessary deflection of needles. Cams 62, 64, 66 and 68 are fully withdrawn and the finger or fingers 182 previously active are raised, this raising being at a point which will cause the yarn or yarns to knit last on the medium butt needle which is trailing behind the long butt needles when the cylinder is traveling in a clockwise direction. These yarns may be clamped and cut, but are preferably allowed to float from this needle to the raised yarn finger. Cams 78 and 80 remain in action since the heel is to be knit at the sole feed. An intermediate portion of cam 154 still engages follower 152 so that the lowering picker remains inactive.

The change to the heel yarn having been made at the sole feed, the narrowing proceeds in the usual manner, the raising pickers 82 and 84 being operative upon the medium and short butt needles, while the long butt needles are raised out of action. When narrowing has been completed, the cam disc is again stepped around. The only effect of this is to bring a high portion of the cam 154 into engagement with follower 152 to rock lever 146 further outwardly and permit the lowering picker 88 to rise and become operative in the usual manner to lower the needles two at a time while the pickers 82 and 84 continue to raise them one at a time.

When the sole is completed the cam disc again advances restoring all of the elements to the positions occupied during the knitting of the high splice, the main yarn or yarns being reintroduced so that the suture needle which last knit again begins knitting while the cylinder travels in a counterclockwise direction. A suitable sole yarn replaces the heel yarn. The movements of the pattern chain continue from the stopping position. Since the operation is the same as that above described during the formation of the high splice it need not be again repeated.

When the sole is completed the cam disc again advances either one step, or, as shown, two steps, one being idle. All fingers 182 are raised out of action, so that withdrawal takes place on the medium butt suture needle following the long butt needles while the cylinder is travelling in a clockwise direction, while the finger 184 which carries the heel yarn is lowered into action to replace the sole yarn finger. Cams 62, 64, 66 and 68 are withdrawn. Switch cam 90 is raised. The needle cylinder rotates. Accordingly, all of the needles knit at the sole feed to form the advanced toe i.

At this time both controls 254 and 260 become active to prevent needle deflection and remain so during the remainder of the formation of the stocking. The pattern chain continues to advance until it is arrested by the action of pin 266 as fully described in the application referred to above. Stopping of the chain will occur at

sometime during the finishing of the stocking. The chain thus becomes ready to properly start the pattern in a subsequent stocking.

After the formation of the several courses forming the advanced toe, the disc 30 again moves bringing the parts into position to perform the narrowing and then the widening for the toe, the motion of the needle cylinder again becoming reciprocatory. The operations in both narrowing and widening resemble those occurring in the formation of the heel and are not, therefore, repeated.

Following the completion of the widening operation, rotary knitting is resumed, the parts being the same as in the formation of the advanced toe. The several courses thus formed constitute the loopers rounds. It may be noted, in this connection, that the same yarn is generally used for the heel, advanced toe, toe, and loopers rounds.

After the loopers rounds are completed the yarn is withdrawn so that the loops are pressed off the needles, the cams are then withdrawn to effect levelling, and the machine stops. The cycle is thus completed, and a new rib top may be transferred to the machine.

During the above cycle of operations various different yarns have been inserted at both feeds. At the instep feed, for example, there is first inserted the extended top yarn which is of comparatively heavy weight and then the main yarns which are of comparatively light weight. Similar changes take place at the sole feed, the high splice and sole yarns being generally lighter than the yarn or yarns constituting the heel, toe, etc. Accordingly, in order to produce proper results, it is necessary that the various cam adjustments heretofore described be used. As pointed out above, the cams at the sole feed are not axially movable during the cycle of operation, adjustment being effected at this point by axial movement of the needle cylinder. As the needle cylinder moves it carries with it the cams at the instep feed supported by the member 110. This, in turn, is adjustable through the medium of the cam 132 as illustrated in Figs. 13, 14 and 15. Suitable cams on the main disc 30 are provided to effect these independent adjustments at the proper times. The action of cam 132 might take place, for example, when the extended top yarn is introduced.

Besides the adjustments mentioned above, it is necessary to provide means for balancing the stitch when wear occurs upon the cams 62, 64, 78 and 80. Accordingly, as pointed out above, these cams are independently adjustable by means of washers. Of course, such adjustment need not be effected during a cycle of the machine but is made when the machine is stationary.

It will be clear that numerous changes may be made in details of construction and also by the replacement of certain mechanism by non-equivalent but analogous mechanism without departing from the spirit of the invention. For example, as mentioned above, the arrangement for carrying the pattern from the leg into the instep continuously without interruption is not confined to a reverse plating mechanism, but it is obvious this same method can be applied to the control of other design forming means.

One modification of particular utility can be attained by the operation of the machine so that knitting occurs at both feeds during rotation. This may be accomplished by a rearrangement of the controlling cams so that cam 78 as well as cam 80 is active and one of fingers 184 is op-

erative to present a yarn or yarns to the needles at the sole feed. By now having the trick wheel 212 alone active, a circular portion will be knitted which will carry designs and have the appearance and construction illustrated in my prior Patent No. 1,805,624, referred to above; that is, having alternate courses formed at the different feeds, one set comprising variously arranged yarns to form designs. By following this with 10 split fabric operation of the type already described but with only one trick wheel, 212, active, the one split portion formed at the instep feed may be given an appearance identical with that of the circularly knit portion, assuming, of course, 15 a suitable selection of yarns at the two feeds.

In the following claims, for simplicity of expression, the term "instep" has been used to apply to the entire front and top split portion of a stocking; that is, it refers broadly to such 20 portions of a stocking as are designated at either *e* or *h*, or both, in Fig. 3. Also where reference is made to a "common" or "same" yarn it will be understood that portions of yarn from the same source are indicated.

25 Certain parts of the disclosed mechanism are not claimed herein being the invention of Harold E. Houseman and being claimed in his application, Serial Number 522,864, filed March 16, 1931.

What I claim and desire to protect by Letters 30 Patent is:

1. A knitting machine including a circular series of needles, elements cooperating with the needles in the formation of stitches, means for presenting yarns to the needles at spaced feeds, 35 cams associated with the feeds for actuating the needles and elements during relative rotary or reciprocatory movements, driving means for effecting such rotary or reciprocatory movements, controlling devices for effecting, first, rotary movements while only one feed is active to produce one portion of fabric, and, secondly, reciprocatory movements while both feeds are active to produce a split portion of fabric having two parts, and means for effecting manipulation 40 of yarns at one feed to produce patterns during reciprocatory knitting, said last named means including two pattern devices one of which is effective during reciprocation in one direction and the other of which is effective during reciprocation in the other direction.

2. A knitting machine including a circular series of needles, elements cooperating with the needles in the formation of stitches, means for presenting yarns to the needles at spaced feeds, 55 cams associated with the feeds for actuating the needles and elements during relative rotary or reciprocatory movements, driving means for effecting such rotary or reciprocatory movements, controlling devices for effecting, first, rotary movements while only one feed is active to produce one portion of fabric, and, secondly, reciprocatory movements while both feeds are active to produce a split portion of fabric having two parts, and means for effecting manipulation 60 of yarns at that feed which is active during rotation to produce patterns during both rotary and reciprocatory knitting, said last named means including two pattern devices one of which is effective during reciprocation in one direction and also during rotation, and the other of which is effective during reciprocation in the other direction.

3. A knitting machine including a circular series of needles, elements cooperating with the 75 needles in the formation of stitches, means for

presenting yarns to the needles at spaced feeds, cams associated with the feeds for actuating the needles and elements during relative rotary or reciprocatory movements, driving means for effecting such rotary or reciprocatory movements, controlling devices for effecting, first, rotary movements while only one feed is active to produce one portion of fabric, and, secondly, reciprocatory movements while both feeds are active to produce a split portion of fabric having two parts, and means for effecting manipulation of 10 yarns at that feed which is active during rotation to produce patterns during both rotary and reciprocatory knitting, said last named means including two pattern devices one of which is effective during reciprocation in one direction and also during rotation, and the other of which is effective during reciprocation in the other direction, and means for maintaining the last named device inoperative during rotation.

4. A knitting machine including a circular series of needles, elements cooperating with the needles in the formation of stitches, means for presenting yarns to the needles at spaced feeds, 15 cams associated with the feeds for actuating the needles and elements during relative rotary or reciprocatory movements, driving means for effecting such rotary or reciprocatory movements, controlling devices for effecting, first, rotary movements while only one feed is active to produce one portion of fabric, and, secondly, reciprocatory movements while both feeds are active to produce a split portion of fabric having two parts, and means for effecting manipulation of 20 yarns at that feed which is active during rotation to produce patterns during both rotary and reciprocatory knitting, said last named means including two pattern devices one of which is effective during reciprocation in one direction and also during rotation, and the other of which is effective during reciprocation in the other direction, and means for maintaining the last named device inoperative during rotation.

5. A knitting machine including a circular series of needles, elements cooperating with the needles in the formation of stitches, means for presenting yarns to the needles at spaced feeds, 25 cams associated with the feeds for actuating the needles and elements during relative rotary or reciprocatory movements, driving means for effecting such rotary or reciprocatory movements, controlling devices for effecting, first, rotary movements while only one feed is active to produce one portion of fabric, and, secondly, reciprocatory movements while both feeds are active to produce a split portion of fabric having two parts, and means for effecting manipulation of 30 yarns at that feed which is active during rotation to produce patterns during both rotary and reciprocatory knitting, said last named means including two pattern devices one of which is effective during reciprocation in one direction and also during rotation, and the other of which is effective during reciprocation in the other direction, and means for rendering both devices 35 inoperative at predetermined times.

6. A knitting machine including a circular series of needles, elements cooperating with the needles in the formation of stitches, means for presenting yarns to the needles at spaced feeds, 40 cams associated with the feeds for actuating the needles and elements during relative rotary or reciprocatory movements, driving means for effecting such rotary or reciprocatory movements, controlling devices for effecting, first, rotary movements while only one feed is active to produce one portion of fabric, and, secondly, reciprocatory movements while both feeds are active to produce a split portion of fabric having two parts, and means for effecting manipulation of 45 yarns at one feed to produce patterns during reciprocatory knitting, said last named means including two pattern devices one of which is effective during reciprocation in one direction and the other of which is effective during reciprocation in the other direction.

7. A knitting machine including a needle cylinder, a circular series of needles carried thereby, and two sets of knitting cams, said cylinder being axially adjustable, one of said sets of cams being axially fixed, and the other set of cams being axially movable during axial adjustment of the cylinder.

8. A knitting machine including a needle cylinder, a circular series of needles carried thereby, and two sets of knitting cams, said cylinder being axially adjustable, one of said sets of cams being axially fixed, and the other set of cams be- 75

ing axially movable during axial adjustment of the cylinder, the last named set of cams being adjustable relatively to the cylinder.

8. A knitting machine including a circular series of needles, elements cooperating with the needles in the formation of stitches, means for presenting yarns to the needles at a feed, means for imparting relative reciprocatory movements to the needles and feed, and devices for effecting manipulation of yarns at said feed to produce patterns during reciprocatory knitting, said devices including two pattern means one of which is effective during reciprocation in one direction and the other of which is effective during reciprocation in the other direction.

9. A knitting machine including a circular series of needles, elements cooperating with the needles in the formation of stitches, means for presenting yarns to the needles at a feed, means for imparting relative reciprocatory movements to the needles and feed, and devices for effecting manipulation of yarns at said feed to produce patterns during reciprocatory knitting, said devices including one means effective to control the formation of designs during reciprocation in one direction, a separate means effective to control the formation of designs during reciprocation in the other direction, and means interrelating the operations of the two controlling means whereby a predetermined design may be formed extending through courses formed during reciprocation in both directions.

10. A knitting machine including a circular series of needles, elements cooperating with the needles in the formation of stitches, means for presenting yarns to the needles at a feed, means for imparting relative reciprocatory movements to the needles and feed, and devices for effecting manipulation of yarns at said feed to produce patterns during reciprocatory knitting, said devices including separate means arranged to selectively manipulate needles on opposite sides of the feed, one acting to effect patterning during reciprocation in one direction and the other acting to effect patterning during reciprocation in the other direction, and means interrelating the operations of said needle manipulating means whereby a predetermined design may be formed extending through courses formed during reciprocation in both directions.

11. A knitting machine including a circular series of needles, elements cooperating with the needles in the formation of stitches, means for simultaneously feeding a plurality of yarns to the needles, pattern controlled mechanism controlling the needles whereby, after they pass beyond the feeding means when moving relatively thereto in one direction, their engagement with said yarns vary, and pattern controlled mechanism controlling the needles whereby, after they pass beyond the feeding means when moving relatively thereto in the opposite direction, their engagement with said yarns vary, whereby the yarns are variously arranged in courses formed during reciprocatory knitting in both directions to form predetermined patterns.

12. A knitting machine including a circular series of needles, elements cooperating with the needles in the formation of stitches, means for simultaneously feeding a plurality of yarns to the needles, pattern controlled mechanism controlling the needles whereby, after they pass beyond the feeding means when moving relatively thereto in one direction, their engagement with said yarns vary to produce selective normal plating

and reverse plating, and pattern controlled mechanism controlling the needles whereby, after they pass beyond the feeding means when moving relatively thereto in the opposite direction, their engagement with said yarns vary to produce selective normal plating and reverse plating, whereby the yarns are variously arranged in courses formed during reciprocatory knitting in both directions to form predetermined patterns.

5

13. A knitting machine including a circular series of needles, elements cooperating with the needles in the formation of stitches, means for simultaneously feeding a plurality of yarns to the needles, pattern controlled mechanism effecting varying manipulations of the yarns whereby, as needles pass beyond the feeding means when moving relatively thereto in one direction, their engagement with said yarns vary, and pattern controlled mechanism effecting varying manipulations of the yarns whereby, as needles pass beyond the feeding means when moving relatively thereto in the opposite direction, their engagement with said yarns vary, whereby the yarns are variously arranged in courses formed during reciprocatory knitting in both directions to form predetermined patterns.

10

14. A knitting machine including a circular series of needles, elements cooperating with the needles in the formation of stitches, means for simultaneously feeding a plurality of yarns to the needles, pattern controlled mechanism effecting varying manipulations of the yarns whereby, as needles pass beyond the feeding means when moving relatively thereto in one direction, their engagement with said yarns vary to produce selective normal plating and reverse plating, and pattern controlled mechanism effecting varying manipulations of the yarns whereby, as needles pass beyond the feeding means when moving relatively thereto in the opposite direction, their engagement with said yarns vary to produce selective normal plating and reverse plating, whereby the yarns are variously arranged in courses formed during reciprocatory knitting in both directions to form predetermined patterns.

30

15. A knitting machine including a circular series of needles, elements cooperating with the needles in the formation of stitches, means for presenting yarns to the needles at a feed, means for imparting relative reciprocatory movements to the needles and feed, and devices for effecting manipulation of yarns at said feed to produce patterns during reciprocatory knitting, said devices including elements located at different positions, one of which elements is effective during reciprocation in one direction and another of which is effective during reciprocation in the opposite direction to produce patterning, and pattern means for controlling said elements.

40

16. A knitting machine including a circular series of needles, a feed, elements cooperating with the needles at the feed to form stitches, means for imparting relative reciprocatory movements to the needles and feed, and means individual to the needles effective during reciprocation in both directions to produce selective relative positioning of the needles and yarns where the needles may take yarns at said feed to produce definite geometrical patterns by selective plating during reciprocatory knitting in both directions.

50

17. A knitting machine including a circular series of needles, elements cooperating with the needles in the formation of stitches, means for presenting yarns to the needles at spaced feeds,

70

60

65

75

cams associated with the feeds for actuating the needles and elements during relative rotary or reciprocatory movements, driving means for effecting such rotary or reciprocatory movements, controlling devices for effecting, first, rotary movements while only one feed is active to produce one portion of fabric, and, secondly, reciprocatory movements while both feeds are active to produce a split portion of fabric having two parts,

and means individual to the needles effective during reciprocation in both directions to produce selective relative positioning of the needles and yarns where the needles may take yarns at one of said feeds to produce definite geometrical patterns by selective plating during reciprocatory knitting in both directions.
